PAIR OF TOY SPECTACLES HAVING REAR VISION MIRRORS

Emil H. Rittmueller, Des Plaines, Ill.

Application August 6, 1957, Serial No. 47,248

Term of patent 7 years

(Cl. D34—15)

Figure 1 is a perspective view of a pair of toy spectacles having rear vision mirrors showing my new design;

Figure 2 is another perspective view thereof; and

Figure 3 is an elevational view thereof, with the bows extending in the plane thereof.

Portions of the drawing figures are diagonally lined to indicate mirror surfaces.

I claim:

The ornamental design for a pair of toy spectacles hav-

ing rear vision mirrors, substantially as shown and described.
